UNITED STATES PATENT OFFICE.

RICHARD HAMMERSLY HEENAN AND RICHARD HURRELL FROUDE, OF MANCHESTER, COUNTY OF LANCASTER, ENGLAND.

ROTARY ENGINE OR PUMP.

SPECIFICATION forming part of Letters Patent No. 312,116, dated February 10, 1885.

Application filed November 18, 1884. (No model.) Patented in England October 2, 1884, No. 13,102.

To all whom it may concern:

Be it known that we, RICHARD HAMMERSLY HEENAN and RICHARD HURRELL FROUDE, citizens of England, both residing at Manchester, in the county of Lancaster, England, have invented an Improvement in Rotary Engines or Pumps, (for which we have made application for a patent in Great Britain, dated October 2, 1884, No. 13,102,) of which the following is a specification.

Our invention relates to the class of spherical rotary engines and pumps for which British Letters Patent were granted to B. Tower, dated October 2, 1879, No. 3,953, and United States Letters Patent were granted to G. Murray, Jr., No. 221,599. United States Letters Patent No. 295,380 were also granted on the 18th of March, 1884, to the said R. H. Froude for certain details of construction of such engines and pumps.

Our present invention has for its object so to construct and arrange several of these details as to obtain increased strength of parts and tightness against leakage, as also to simplify and cheapen their construction, as we will describe, referring to the accompanying drawings.

Figure 1 is a front view, and Fig. 2 a plan, of the central piston or diaphragm, which revolves and is balanced within the spherical shell. Fig. 3 is an elevation of the two transversely crossing central pins which form the joint-pins of the two revolving and oscillating blades. Fig. 4 is a side view, and Fig. 5 a plan, of one of the packings of the piston. Fig. 6 is an elevation, partly in section, of the two blades and part of the piston to which they are jointed. Fig. 7 is a back view, and Fig. 8 a plan, of one of those blades. Fig. 9 is a side view, and Fig. 10 a plan, of one the packings of the blades. Fig. 11 is an elevation, and Fig. 12 a plan, of one of the end packings at the joints of the blades to the piston. Fig. 13 is an elevation, and Fig. 14 a plan, of one of the bushes for the joint-pins.

The piston A has bored through its middle two holes at right angles to one another to receive the two joint-pins. One of these, B, made in one piece, is passed into one of the

holes of the piston, the other is made in two parts, B', terminating in a part of smaller diameter screw-threaded, and B² made with a threaded hole at its end to receive the screwed end of B', so that after putting B in position in the one hole of A, the parts B' and B² are introduced from opposite sides and secured together by screwing.

To prevent B' from unscrewing, a pin, b, is inserted after B' is screwed home. B² is prevented from turning round by the miter fitting of its end to the recessed bed formed for it in B. The bosses of the blades D are bored sufficiently large to admit bushes C, which fit the outer ends of the pins B, and are screwed into the bosses of the blades, being prevented from unscrewing by pins c, passed through them and the bosses of the blades D. Each blade D and D' is made in one piece with its shaft E E'.

The packings are of the following kind: the piston A is packed at four places, in each case by two pieces, a a, let into grooves formed in the periphery of the piston, and separated by a wedge-piece, a', that is pressed outward by a helical spring, a''. It will thus be seen that the pieces a a and spring-actuated wedge-piece a' constitute a separate or distinct unitary packing, and that it is essential in practical working of the piston that one of the unitary packings be inserted separately as a complete fixture within each of the series of grooves or recesses in the piston-head. The blades D D' are also packed at two places of each, in each case by two pieces, d d, separated by a wedge-piece, d', that, like a', is pressed outward by a spring.

Into a recess in each of the blade-bosses is inserted a horseshoe-piece, G, which is pressed outward by a pair of springs, g g, and also by the outward tendency of the packing-pieces d, which are shouldered down at d' to admit G.

Having thus described the nature of our invention and the best means we know of carrying it into practical effect, we claim—

1. In a spherical rotary engine or pump, the combination of the transversely-bored piston, A, the joint-pins B, B', and B², the bossed blades D D', and their bushes C, as means of jointing the blades to the piston, substantially as described.

2. In combination with a spherical rotary engine or pump, a piston-head having a series of separate recesses located at intervals in its periphery, with a unitary packing composed of the pieces *a a*, and spring-actuated wedge-piece *a'*, seated within each of the recesses, substantially as described.

3. In a spherical rotary engine or pump, in combination with the blades *D D'*, the packing-pieces *d*, their wedge-pieces *d'*, and springs *d²*, the horseshoe-pieces *G*, and their springs *g*, substantially as described.

In testimony whereof we have signed our names to this specification, in the presence of two subscribing witnesses, this 5th day of November, A. D. 1884.

RICHARD HAMMERSLY HEENAN.
RICHARD HURRELL FROUDE.
